SECTIONAL FUEL DISTRIBUTOR

Howard P. Anderson, Erie, Pa., assignor to The
Standard Stoker Company, Inc., a corporation
of Delaware

Application November 24, 1933, Serial No. 699,525

4 Claims. (Cl. 110—101)

This invention, which relates to improvements in sectional fuel distributors for use in connection with stokers, has for its principal object the provision of a sectional fuel distributor 5 wherein the separable sections comprising the distributor are firmly secured in a manner so that adjacent surfaces are in contact with each other, resulting in better conductivity of heat from one section to another. Thus the front 10 section of the distributor which is subjected to the intense heat within the firebox, is firmly secured to the rear section which has a portion lying outside the firebox, thereby transmitting the heat to this cooler rear section for dissipation. In this manner, the life of the front section is prolonged.

A further object of this invention is the provision of a fuel distributor of the type specified comprising separable front and rear sections, the 20 rear section having a ledge underlying the front section and being provided with means for restraining downward movement of said front section so that when the securing means which holds these sections together is removed, the front section will not fall onto the firebed.

To those skilled in the art the advantages of my invention will be apparent when the following specification is read in connection with the drawings, in which

30 Figure 1 is a longitudinal sectional view taken through the firing opening of a furnace with a stoker embodying my invention in similar section, parts thereof being shown in elevation,

Figure 2 is a plan view of parts shown in Figure 1 taken on line 2—2 thereof,

Figure 3 is an isometric view of the rear section of the novel sectional distributor,

Figure 4 is an isometric view of the front section of the novel sectional distributor, and

40 Figure 5 is a transverse cross sectional view of the fuel distributor taken on the line 5—5 of Figure 2.

These drawings illustrate a furnace 10 having a wall 11 with the usual firing opening 12 there-through. Fuel is fed into the furnace 10 through the firing opening 12 by means of a stoker S which includes the discharge conduit 13 having a fuel delivery mouth 14 in open communication with the firing opening 12. The fuel is urged 50 through the discharge conduit 13 and then passes through the delivery mouth 14 onto the fuel supporting surface 15 of the distributor D. A pressure fluid head 16 issues blasts of pressure fluid through the jet openings 17 which sweep the fuel across the fuel supporting surface of the distributor D and thence over the firebed in the furnace.

The above described construction is not new in itself; the present invention resides in the 60 novel form of the fuel distributor D, which will

now be described in detail. The distributor D includes the front section 18 and the rear section 19, the former extending into the furnace while the latter is received in a recess 20 formed in the bottom of the stoker delivery mouth 14. 5 The rear section 19 is provided with a flange 21 through which are passed the bolts 22 for securing this section of the distributor to the stoker discharge conduit.

At its forward end, the rear section 19 is provided with a recess 23 into which is fitted the rearward extension 24 of the front section 18. Disposed within the recess 23 are the ledges such as 25, each of which underlies the rearward extension 24 of the front section for supporting 15 the same. It will be observed from the drawings that the ledges 25 are disposed below the fuel supporting surface 15. A threaded stud or projection such as 26 is screwed into an opening 27 in each ledge 25; the upper end of each stud 20 26 is preferably slightly below the plane of the fuel supporting surface 15. Each ledge 25 is joined with the main portion of the rear section 19 by a rear wall 28 and a side wall 29.

Preferably, the ledges 25 are spaced apart 25 in the recess 23 and form therebetween a passage 50 which registers with a passage 51 formed in the front section 18. The passage 51 extends toward the front wall 52 of the front section 18 between the fuel supporting surface 15 and the bottom wall 54 of the front section 18, the said front wall being apertured by holes such as 53 whereby air is entrained from a point exterior of the firebox through the passages 50, 51 for cooling the front section. If desirable, the 30 bottom wall 54 of the front section may also be perforated as at 55.

The rearward extension 24 of the front section 18 is apertured by holes such as 30, each of which passes freely over its respective stud 26. Concentric with each hole 30 is a counter-bored portion 31 bored from the fuel supporting surface 15 of the distributor downwardly a distance sufficient to receive a nut 32 and a lock washer 33. The nut 32 engages the threaded stud 26 and is 40 drawn tightly by a socket wrench which fits into the counter-bored portion 31. When the nuts 32 are drawn tightly, the underside wall 34 of the rearward extension 24 seats firmly on the ledges 25, producing a rigid connection between 45 the front section 18 and the rear section 19 and also a better conduction of heat from the front section to the rear section is made possible by this construction. Thus, heat is dissipated from that portion of the distributor which extends 50 into the furnace to the cooler rear section 19, thereby increasing the life of this renewable 55 front section.

In the well known "B-K Stoker" embodying my present invention, the pressure fluid head 16 60

is disposed rearward of the furnace wall 11 and the distributor D extends forwardly therefrom into the furnace 10. In this type of stoker it is necessary to provide fuel deflecting means for the purpose of diverting a portion of the fuel to the rear corners of the furnace. This deflecting means includes fuel pockets such as 35, one at each side of the distributor D. These pockets 35 are formed by a wall 36 which slopes downwardly and forwardly from the fuel supporting surface 15. Each pocket 35 opens laterally toward its respective side of the furnace and as the fuel is swept across the fuel supporting surface 15, these pockets intercept a portion of the fuel and deflect it laterally. It will be observed from Figures 3 and 4 that the front section 18 and the rear section 19 carry portions of these sloping walls 36 forming the fuel pockets 35 and when these two sections are assembled, the sloping wall portions 20 constitute in effect a single continuous wall 36 at each side of the distributor. In practice I have found it advisable to dispose the securing means for the two sections inwardly of this sloping wall 36 in order that no part of such securing means 25 would protrude into the path of the fuel passing through the pockets 35.

Whenever the front section 18 is warped or otherwise damaged due to the intense heat in the furnace, the firedoor 37 or the hinged cover 38 30 may be opened and the threaded nuts 32 unscrewed by means of a socket wrench. By the use of the studs or projections 26, the front section 18 will not fall forwardly into the furnace 10 when the nuts 32 are removed and thus the assembly and disassembly of the two sections is simplified.

I claim:

1. A sectional fuel distributing plate for stokers comprising a front section and a rear section having a fuel supporting surface, the forward portion of said rear section being provided with a recess intermediate the sides thereof, transversely extending wall portions depending from said rear section along the inner edge of said recess, a pair 45 of longitudinally extending walls depending from said rear section along the side edges of said recess, a ledge joining the lower edge of each of said transverse wall portions and the lower edge of a respective longitudinal wall forming supporting means, each ledge carrying an upstanding threaded projection, the portion of the fuel supporting surface of said rear section on each side of said recess sloping forwardly and downwardly below the plane of the surface of the rear section 50 rearward of said recess, the rearward portion of said front section being provided with a rearward extension fitted in said recess and seated on said supporting means, said rearward extension engaging said threaded projections, a threaded member 55 engaging each of said threaded projections for firmly securing the front section to the rear section, said front section having lateral extensions lying in a plane below the surface thereof and forming pockets therewith, said extensions forming continuations of the sloping portions of said rear section.

2. As a new article of manufacture, a rear section of a fuel distributing plate for stokers including a fuel supporting top wall, said top wall 70 being provided with a recess in its forward end intermediate the sides thereof, transversely extending wall portions depending from said top wall along the inner edge of said recess, said de-

pending wall portions being spaced apart to form an opening therebetween, the portion of said top wall on each side of the recess therein sloping forwardly and downwardly below the plane of the top wall rearward of said recess, a pair 5 of longitudinally extending walls depending from said top wall along the side edges of the recess therein, ledges at the sides of the opening between said transverse depending wall portions joining the lower edges of said transverse wall portions and the lower edges of said longitudinal walls and lying in a plane below said fuel supporting top wall, each of said ledges being provided with an upstanding threaded element.

3. A sectional fuel distributing plate for stokers comprising a front section and a rear section, each of said sections having a fuel supporting surface, the forward portion of said rear section being provided with a recess intermediate the sides thereof, ledge-like supporting means extending forwardly from said rear section, below the level of its fuel supporting surface and between the sides and inner edges of said recess, said supporting means carrying a plurality of upstanding threaded projections, the portion of the fuel supporting surface of said rear section on each side of said recess sloping forwardly and downwardly below the plane of the surface of the rear section rearward of said recess, the rearward portion of said front section being provided with a rearward extension fitted in said recess and seated on said supporting means, said rearward extension engaging said threaded projections, and a threaded member engaging each of said threaded projections for firmly securing the front section to the rear section, said front section having lateral extensions lying in a plane below the surface thereof and forming pockets therewith, said extensions forming continuations of the sloping portions of said rear section. 40

4. A sectional fuel distributing plate for stokers comprising a front section and a rear section, each of said sections having a fuel supporting surface, the forward portion of said rear section being provided with a recess intermediate the sides thereof, ledge-like supporting means formed with said rear section and lying in a plane below the fuel supporting surface of said rear section and between the side and inner edges of said recess, said ledge-like supporting means carrying a plurality of upstanding threaded projections rigidly secured therewith and terminating at their upper ends below the level of the fuel supporting surface of said rear section, said front section having a rearward extension intermediate its sides fitting in said recess and seated on said supporting means, the top face of said extension forming a portion of the fuel supporting surface of said front section, the extension of said front section being provided with a plurality of holes therethrough receiving the threaded projections of said ledge-like supporting means for loosely holding said front and rear sections together, the diameter of the threaded projections above said supporting means being less than the diameter of the holes in said front section, and threaded members threaded on said threaded projections for rigidly securing said front and rear sections together, said members having no part thereof extending above the plane of the fuel supporting surface of said front section. 55 60 65 70
